UNITED STATES PATENT OFFICE.

ARTIS CHESTER BRYAN, OF SYRACUSE, NEW YORK.

LEVER LOCK.

Application filed October 4, 1921. Serial No. 505,431.

To all whom it may concern:

Be it known that I, ARTIS C. BRYAN, of Syracuse, in the county of Onondaga, in the State of New York, have invented new and 5 useful Improvements in Lever Locks, of which the following, taken in connection with the accompanying drawings, is a full, clear, and exact description.

This invention relates to a lever lock but 10 more particularly to a device for locking the gear shifting levers of motor vehicles to reduce the liability of theft and other unauthorized use of the machine.

These levers are usually fulcrumed by a 15 universal joint upon a suitable supporting base or housing on the frame of the machine, the fulcrums being usually arranged a relatively short distance above the lower ends of the levers for operative connection 20 with the gear shifting rods to permit the lever to be shifted laterally and forwardly and rearwardly from a neutral position for gear shifting purposes.

One of the objects of my invention is to 25 provide simple, compact and efficient means for engaging the lower end of the lever some distance below the fulcrum and holding said lever in its neutral position against initial lateral movement in either direction.

30 In other words, I have sought to incorporate in the base or housing a more compact and sturdy locking device than has heretofore been practiced, by the use of a locking bolt having one end engaged with opposite 35 sides of the lower end of the lever and its other end slidably in a suitable guide in the base and held in its locking position by a ball tumbler controlled by a key operated barrel.

40 Another object is to enable the various parts of the locking device to be assembled or removed without disturbing the shifting lever.

45 Other objects and uses relating to specific parts of the locking device will be brought out in the following description:

In the drawings:

50 Fig. 1 is a horizontal sectional view of a lever locking device embodying the various features of my invention taken in the plane of line A—A, Fig. 2.

Fig. 2 is a vertical sectional view of the same device taken in the plane of line B—B, Fig. 1.

55 Fig. 3 is a vertical sectional view taken in the plane of line C—C, Fig. 2.

Fig. 4 is a detail sectional view taken in the plane of line 4—4, Fig. 1 showing the means for locking one of the clamping bolts of the lever-support against removal from 60 the transmission gear-case.

As illustrated, this device comprises a one-piece hollow cast metal base or housing 65 —1— adapted to be secured in any well known manner to the frame of the machine and provided with an upright conical portion —2— having a central spherical seat or bearing —3— in its upper end, which is milled externally for receiving a sheet metal cap —4—.

70 A gear shifting lever —5— is extended vertically through a central opening —6— in the top of the housing —1— and is provided with a substantially hemispherical enlargement —7— normally resting on the spherical seat —3— and forming therewith a universal joint to permit the lever to swing in any direction about the center of the spherical bearing.

75 The hemispherical enlargement —7— is intermediate the ends but preferably nearer the lower end of the lever —5— so that the upper end of said lever extends a considerable distance above the top of the housing and constitutes the handle by which said lever may be rocked upon its seat —3—, the lower and relatively shorter arm as —8— of the lever being extended through the bottom of the housing for engagement with the gear shifting members not shown and is provided with annular enlargements —9— and —10— in vertically spaced relation one above the other between the lower spherical end —11— and enlargement —7—, the annular enlargement —9— being provided 80 with longitudinally convex surfaces for engagement with the locking bolt hereinafter described, while the annular enlargement —10— is disposed in a plane just below the locking bolt to prevent vertical withdrawal 85 of the lever from its operative position.

90 The upper end of the cap —4— is spherical and provided with a central opening —12— of sufficient diameter to permit the desired rocking movement of the lever —5—, said opening being closed by a supplemental spherical cap —13— preferably of sheet metal engaging the inner face of the spherical portion of the cap —4— for lateral sliding movement therein and is yieldingly held against said face by means of a coil spring —14— interposed between the sup- 95 100 105 110

plemental cap —13— and upper face of the annular enlargement —7— as shown in Fig. 3, said supplemental cap being provided with a central opening —15— of just sufficient size to easily receive the adjacent portion of the lever —5— and to move therewith as the lever is rocked about the center of the spherical bearing —3—.

The lever locking device comprises a locking bolt —16— having a cylindrical shank —17— slideable horizontally in a radial guide opening —18— and provided with a forked inner end forming a slot —19— extending transversely of the axis of said bolt 15 in the horizontal plane of the annular enlargement —9— of the lever —5—, the opposite walls of the slot being straight transversely and extended some distance to opposite sides of the axis of the lever for engaging 20 opposite faces of said enlargement, whereby the movement of the lever laterally in opposite directions will move the locking bolt —17— axially in reverse directions.

On the other hand, if the locking bolt 25 is held against axial movement, it will also hold the lever —5— against lateral movement or in its neutral position. The shank of a locking bolt is provided with a lengthwise key-way —20— in one side engaged 30 by a key —21— on the inner end of a screw —22—, which engages in a threaded aperture —23— in the corresponding side of the housing —1— for holding the locking bolt against turning movement in the bearing 35 —18— and thereby maintaining the inner U-shaped head in a substantially horizontal position when the locking bolt is adjusted for use.

The opposite side of the shank of a locking 40 bolt is provided with a vertical groove —24— adapted to receive a portion of a locking ball —25—, which is movable in a guide opening —26— leading radially from the bearing —18— to an upright opening 45 —27— in which latter is mounted a barrel —28— forming an extension of a key-lock —29— which in turn is rigidly secured in a socket —30— in the upper end of an offset portion —31— of the base or housing 50 —1— as shown in Fig. 2.

The adjacent ends of the barrel —28— and the lock —29— are provided with tongue and groove connections —32— for transmitting motion for the turnable member of the lock —29— to said barrel, said turning member being adapted to be operated by means of a key —33— capable of removal and reinsertion when desired.

The barrel —28— extends across the passage —26— and is provided with a recess —34— movable into and out of registration with the recess —26— in the shank of the locking bolt —16— as the barrel —28— is turned through the medium of the key 60 —33—. These recesses —26— and —34—

are of sufficient length to receive portions of the ball-lock or tumbler —25— which is of substantially the same diameter as that of the passage —26— with just sufficient clearance to permit the ball to move in said passage without excessive friction.

The distance between the periphery of the cylindrical shank —17— of the locking bolt —16— and inner wall of the recess —34— is slightly greater than the diameter of the ball to allow said ball to clear the periphery of the shank —18— when entering the recess —34— alined therewith, thus permitting the free endwise movement of the locking bolt by the action of the lever —5— in shifting the gears.

The distance between the center of the lever —5— and recess —24— along the axis of the locking bolt is substantially equal to the distance between the vertical axis of the universal joint of said lever and center of the guide opening —26— for the ball —25—, and it therefore, follows that when the lower end of the lever is brought to a vertical or neutral position, the recess —24— will be registered with the guide opening —26— and ball —25— therein, and, when it is desired to lock said lever in said neutral position, it is simply necessary to turn the barrel —28— through the medium of the key —33— one-quarter turn in either direction or sufficient to move the recess —34— out of registration with the guide opening —26—, whereupon the periphery of the barrel —28— at its junction with the inner wall of the recess —34— will act as a cam for forcing the ball —25— into the registering recess —34— of the locking bolt for locking and holding the lever —5— in its neutral position, whereupon the key —33— may be removed by the operator to prevent the operation of the shifting lever and parts actuated thereby.

On the other hand, by reinserting the key —33— in the lock —29— and turning the barrel —28— to bring its recess —34— into registration with the ball —25— allows the locking bolt —16— to be moved endwise by the lever —5— during which operation, the end walls of the recess —24— will force the ball —25— into the recess —34— out of the path of movement of said locking bolt.

The annular flange or enlargement —10— on the lower end of the lever —5— normally lies in a plane just below the inner end of the locking bolt —16— and serves to prevent upward displacement of the lever from its operative position.

The inner U-shaped end of the locking bolt —16— is offset normally below the axis of the shank —17— to facilitate the removal and reinsertion of said locking bolt without removing the shifting lever —5—, this being accomplished by simply unscrewing the screw —22— sufficiently to disengage it

from the key-way —20— which permits the locking bolt to be turned a one-quarter turn to the position shown by dotted lines in Fig. 1 when the recess —34— is registered with the ball —25—, whereupon the lever —5— may be rocked a sufficient distance to bring its lower end out of engagement with the U-shaped end of the locking bolt and to one side of the shank thereof, whereupon said locking bolt may be withdrawn inwardly and removed from the underside of the base when the latter is detached from the frame.

The spring —14— in addition to holding the member —18— against the inner face of the cap —4— also bears against the upper flat face of the part —7— and serves to yieldingly hold the lever —5— in its neutral position when the bolt —17— is unlocked.

The lever-supporting base or housing —1— constitutes a cover-plate for a transmission gear-case —G— Figure 4 and is clamped thereto by any suitable number of bolts as —35— engaging in threaded sockets —36— in the gear-case —G— and passing loosely through openings —37— in the housing —1—, one of said bolts nearest the lock-barrel —28— being provided with a recess —38— adapted to register with a supplemental locking member —39—, which is movable in a radial opening —40— in the base or cover-plate —1— into and out of the recess —38— and is also movable into and out of a supplemental recess —41— in the barrel —28—, the inner wall of said recess —41— serving as a cam by which the locking member —39— may be forced into the recess —38— of the clamping bolt —35—, the lock said bolt against turning simultaneously with the locking of the sliding bolt —17— which holds the lever —5— against rocking movement when the barrel —28— is turned to its rocking position through the medium of the key —33—.

This locking of the clamping bolt —35— prevents malicious removal of the housing —1— from the gear-case and thereby prevents unauthorized operation of the gear-shifting mechanism, thus producing a double lock to prevent theft of the machine upon which the device is used, it being understood that the unlocking of the barrel —28— will simultaneously release the locking bolt —17— and will also release the clamping bolt —35— to permit the removal of the housing if necessary.

What I claim is:

1. In a lever lock of the character described, the combination of a supporting base, a lever fulcrumed thereon, a locking bolt slidably mounted on the base and provided with means for engaging opposite sides of the lever, said bolt being provided with a recess on one side movable into and

out of registration with an opening in the base, a locking member movable in said opening, and key operated means for forcing and holding said locking member into said recess when the latter is registered with said opening.

2. The combination with a gear shifting lever and a support therefor, a locking bolt engaging opposite sides of the lever and actuated thereby as the lever is shifted laterally to and from a neutral position, a locking member movable in an opening in the support, said locking bolt having a recess movable into and out of registration with said locking member and registering with said locking member when the shifting lever is in a neutral position, and key operated means for forcing the locking member into said recess when the latter is registered therewith.

3. The combination with a gear shifting lever and a support therefor, of a locking bolt slidable on the support and engageable opposite sides of the lever to be operated by said lever when the latter is shifted laterally, a rotary key operated barrel mounted on the support, a locking member between the barrel and locking bolt and actuated by said barrel for engaging and locking the bolt when the latter is shifted to a neutral position by the operation of the gear shifting lever.

4. The combination with a gear shifting lever and a support therefor, a locking bolt engaging opposite faces of the lever for movement therewith as the lever is shifted from a neutral position, said locking bolt having a recess in one side adapted to register with an opening in the support when the lever is in its neutral position, a ball movable in said opening, and key operated means for forcing the ball into the registering recess of the locking bolt.

5. In combination with a transmission gear-case, a cover therefor, means including a clamping bolt for securing the cover to the gear-case, a shifting lever mounted on the cover-plate, a locking-bolt for holding the shifting lever in its neutral position, a key operated member, means actuated by said key operated member for locking the shifting lever in its neutral position, and additional means actuated by the same key-operated member for locking the clamping bolt against removal.

6. In a lever lock, the combination of a gear case, a cover for the gear case, a gear shifting lever fulcrumed on the cover, key-operated means for locking the lever in its neutral position, and means including a locking member actuated by a part of said key-operated means for locking the cover to the gear case when the shifting lever is locked.

7. In a lever lock, the combination of a

- gear case having a cover, a gear shifting lever fulcrumed on the cover, a locking bolt 5
slidable axially in an opening in the cover, and provided with a transversely elongated
slot at right angles to its axis for receiving
a portion of the lever and permitting said
lever to move transversely of said axis relatively to the bolt, the axial width of the slot
being substantially equal to the diameter
10 of the portion of the lever therein to hold
the bolt and lever against relative movement lengthwise of said axis, and key-operated
means for locking the bolt against axial movement when in its neutral position.
15 8. The combination with a gear shifting

lever and a support therefor, of a bolt slideable in an opening in the support and operatively connected to the lever to move therewith as the lever is shifted laterally, a locking member movable in an opening in 20
the support into and out of locking engagement with the bolt, and key-operated means for forcing the locking member to its locking position.

In witness whereof I have hereunto set 25
my hand this 27th day of September, 1921.

ARTIS CHESTER BRYAN.
